SHOE MAKING APPARATUS

Filed June 8, 1927

UNITED STATES PATENT OFFICE.

HEINRICH MAX COLDITZ, OF DRESDEN, GERMANY.

SHOEMAKING APPARATUS.

Application filed June 8, 1927. Serial No. 197,504.

This invention pertains to apparatus for use in making and repairing boots or shoes and more particularly to apparatus for use in attaching outer soles. A process of attaching outer soles by the use of adhesives has recently been perfected, such process comprising the employment of a waterproof and durable cement, such for example as a solution of celluloid or the like and the maintenance of intimate contact between the parts to be connected for a period sufficient to permit the cement to set thoroughly. This process is highly advantageous in repairing shoes by reason of its ease and simplicity, but repair work is commonly done in the home or in relatively small cobbling shops and as most of the presses at present available are complicated and expensive, this process of repair has not been adopted as widely as could be desired. Accordingly the present invention has for its object the provision of a press capable of applying the desired degree of pressure for attaching the sole to a shoe, in accordance with the above described process, and which is simple in construction and mode of operation and which can be sold at a reasonable price.

With the above object in view I have devised a process embodying the features disclosed by way of example in the accompanying drawings in which,

Fig. 1 is a plan view of the frame and bed plate of the press, omitting the resilient pad and the pressure applying yoke;

Fig. 2 is a fragmentary side elevation of the press, showing the yoke in operative position and indicating a shoe in broken lines;

Fig. 3 is a fragmentary vertical section substantially on the line 3—3 of Fig. 1, showing the yoke in operative position; and

Fig. 4 is a vertical section substantially on the line 4—4 of Fig. 2.

Referring to the drawings the press comprises a frame 1 which may conveniently be made of cast iron or steel and which is preferably provided with an upstanding peripheral rim 2 encircling a cavity 3 adapted to receive the forepart of the shoe which is to be provided with a sole. Within this cavity I arrange a bed plate upon which the shoe is supported during the sole-applying operation. This bed plate comprises a central part 4, preferably integral with the frame, and having the upper surface 4^a. To the front and rear of this central part 4, the bed plate of the frame is provided with webs 5 and 6 (Fig. 3) connecting the part 4 with the ends of the frame. The parts 5 and 6 are preferably disposed somewhat below the part 4 and at their outer ends are furnished with bosses or thickened portions provided with screw-threaded openings for reception of the adjusting screws 7 and 8. The rear end of the frame may if desired be provided with a transverse leg or legs 1^a and as here illustrated the forward end of the frame is supported upon the lower end of the adjusting screw 7. I contemplate however that a leg or legs similar to the leg 1^a may be provided at the forward end of the frame if desired.

The bed plate also comprises a movable front part 9 and a movable rear part 10. The parts 9 and 10 are preferably hinged to the central part 4 by means of hinge members 11 and 12. These hinge members may conveniently consist of strips of leather or the like, or if desired the parts 9 and 10 may be united to the frame by means of metallic hinges, pivots or equivalent devices. The parts 9 and 10 may be of metal, wood or any suitable material having the necessary rigidity and strength and as here shown the rear member 10 is preferably angular so that its rear portion inclines upwardly with respect to its forward portion. The parts 9 and 10 rest upon the adjusting screws 7 and 8 respectively and by turning these screws the inclination of the parts 9 and 10 with respect to the central part of the bed plate may be varied independently of one another so as to accommodate the bed plate to shoes of different sizes and longitudinal curvature. Under all ordinary circumstances the bed plate is concave in a front to rear direction by reason of the inclination of the parts 9 and 10 relating to the central part 4. It is also concave transversely, the central part 4 of the bed plate being transversely concave, as shown in Fig. 4, and the parts 9 and 10 also being concave in this direction if desired.

The bed plate comprising the central part 4 and the movable end parts 9 and 10 preferably supports a thick resilient pad 14 comprising one or more layers of rubber or other suitable material adapted to conform closely to the under surface of the shoe sole. This pad may, if desired, have a molded upper surface and be provided with upstanding humps or projections 15 at its rear part adapted to engage the shank portion of the shoe.

The frame 1 is provided with downwardly

directed flanges 16 and 17 in its opposite sides in the region of the fixed bed plate member 4 and these flanges are furnished with elongate substantially horizontal channels 18 and 5 19 in their outer surfaces respectively. The upper walls of these channels are preferably inclined inwardly and upwardly so as to produce overhanging beveled ribs or flanges 20 and 21 respectively. The lower walls of 10 these guide channels may conveniently be formed by attaching plates 22 and 23 to the lower edges of the flanges 16 and 17.

The press also comprises a yoke 24 having spaced depending legs 25 and 26 which straddle the frame and bed plate. The leg 25 is provided at its lower end with an inwardly directed lug 27 engaging the channel 18 while the leg 26 is provided with an inwardly directed lug 28 at its lower end engaging the 20 channel 19.

The lower surface of each of the lugs 27 and 28 is preferably of arcuate curvature as indicated at 29, such surface resting upon the lower wall of the corresponding guide 25 groove. The upper surface of each lug is likewise of arcuate curvature, preferably of greater radius than the lower surface 29, and is beveled as indicated at 30 to fit snugly against the beveled upper wall of the corresponding channel. The lugs 27 and 28 are 30 free to move longitudinally of their respective channels and may also rock or swing within the channels.

The upper or central part of the yoke 24 is 35 provided with a screw-threaded bore for the reception of a pressure-applying screw 31 having a handle 32 and a pressure-applying pad 33 at its lower end, such pad preferably being swiveled as indicated at 34 to the screw 31.

In using this press a last is first inserted in the shoe, and the shoe indicated at 35, the sole 36 cemented thereto by means of suitable cement, is set down upon the bed plate of 40 the press and the ends 9 and 10 are adjusted in accordance with the size and curvature of the shoe until the pad of the bed plate conforms closely to the shoe sole. It is understood of course that before placing the shoe upon the bed plate the screw 31 will have been retraced to provide sufficient space between the pad 33 for the introduction of the shoe. The entire yoke 24 is now moved endwise, the lugs 27 and 28 sliding in their respective guide grooves until the pad 33 is 45 positioned at the proper point to engage the forepart of the shoe upper. The yoke may now be rocked so as to cause the axis of the screw 31 to assume the desired direction and the screw 31 is then turned by means of the handle 32 to apply pressure to the shoe. The tendency of the yoke to shift during the application of this pressure when the pressure is other than vertical, is substantially overcome by the action of wedge-like surfaces 50 55 60 65 70 75 80 85 90 95 100 105 110 115 120 125 130 30

of the lugs 27 and 28 engaging the inclined upper walls of the guide channels.

The shoe is allowed to remain under pressure in the press until the cement has thoroughly set, whereupon the screw 31 is retracted sufficiently to permit removal of the shoe. 70

While I have shown one desirable embodiment of the invention herein I wish it to be understood that I am not to be restricted to the specific details of construction herein illustrated or to materials above referred to as desirable for making the several parts or to the exact dimensions or relative proportions of parts herein referred to except as defined by the claims. 75 80

I claim:

1. A sole cementing press having a frame, a bed plate carried thereby, said frame having guide channels at its opposite sides, a yoke having spaced legs, a lug carried by each leg, said lugs engaging and being movable longitudinally of the respective guide channels, and a pressure device carried by the yoke, the yoke being free to swing about a transverse axis defined by the lugs. 85 90

2. A sole cementing press having a frame, a bed plate carried thereby, said frame having elongate guide channels at its opposite sides, a yoke having spaced legs straddling the frame, a lug provided with an arcuate peripheral surface projecting inwardly from each leg of the yoke into the adjacent guide channel, said lugs providing rockers about which the yoke may swing, and a pressure-applying screw carried by the yoke. 100

3. A sole cementing press having a frame, a bed plate carried thereby, said frame having elongate guide channels at its opposite sides, the upper walls of said channels being inwardly and upwardly inclined, and a yoke having legs straddling the bed plate, each leg having an inwardly projecting lug adjacent to its lower end, said lugs projecting into the adjacent guide channels and having beveled upper surfaces engaging the inclined upper walls of the respective channels. 105 110

4. A sole cementing press having a frame, a bed plate carried thereby, said frame having elongate guide channels at its opposite sides, the upper walls of said channels being inwardly and upwardly inclined, and a yoke having legs straddling the bed plate, each leg having a projecting lug adjacent its lower end, said lugs projecting into the adjacent guide channels, each lug having an arcuate upper surface beveled to fit against the inclined upper wall of its respective groove and forming rockers about which the yoke may swing, and a pressure-applying device carried by the yoke. 115 120 125

5. A sole cementing press having a frame, a bed plate carried thereby, said frame having elongate guide grooves at its opposite sides, the grooves having upper and lower 130

walls, and a yoke straddling the frame, said yoke having lugs projecting inwardly into the respective grooves, each lug having arcuate upper and lower surfaces engaging the upper and lower walls respectively of the groove, said lugs being movable longitudinally of the groove, and a pressure-applying device carried by the yoke.

6. A shoe sole cementing press comprising a frame and a bed plate carried thereby, the bed plate being concave both transversely and from the front to rear, said bed plate comprising a fixed central part and movable front and rear parts, independent adjusting screws for adjusting front and rear parts relatively to the cen-

tral part, one at least of said screws forming a supporting lug for the frame, the frame having guide channels at its opposite sides, a pressure applying yoke having spaced legs straddling the frame, each leg having a lug projecting into the adjacent channel of the frame, the lugs being free to slide in the channels and constituting rockers about which the yoke can swing, and a pressure applying screw carried by the yoke, said screw supporting a pad for engagement with the fore part of a shoe resting on the bed plate.

Signed by me at Dresden, Germany, this tenth day of May, 1927.

HEINRICH MAX COLDITZ.
